C. G. E. JOHNSON

CLAMP

Filed Jan. 25, 1926

INVENTOR.

CARL G.E. JOHNSON

BV

Fred H. Hayn.

ATTORNEY:

UNITED STATES PATENT OFFICE.

CARL G. E. JOHNSON, OF LOS ANGELES, CALIFORNIA.

CLAMP.

Application filed January 25, 1926. Serial No. 83,498.

My invention relates to clamps, and more particularly to devices for securely holding a scraper blade in position so that it may be sharpened.

As is well known, the blades used in connection with floor scrapers frequently require sharpening, and so far as I am aware no device has heretofore been proposed for holding said blades in position so that they may be sharpened.

It accordingly is an object of my invention to provide a novel form of device comprising a set of stationary and movable members for firmly holding a floor scraper blade in position so that it may be sharpened, a suitable base, equipped with an adjustable support, if desired, being provided to hold said base in convenient position, a preferably spring-pressed means being associated with at least one of said members for accommodating blades of different sizes, and for holding and releasing said blade.

A further object of my invention is to provide a novel form of device which is simple in character, easy and inexpensive to manufacture, composed of a minimum number of parts, and one which will thoroughly and reliably effect the objects intended.

Further objects and advantages of my invention will become more apparent as the description thereof proceeds.

Reference is had to the accompanying drawings, in which similar reference characters denote similar parts. In the drawings,

Fig. 1 is a top plan view of my invention,

Fig. 2 is a transverse cross-sectional view on the line 2—2, Fig. 1,

Fig. 3 is a longitudinal cross-sectional view on the line 3—3, Fig. 1, but of a slightly modified form of my invention,

Fig. 4 is a transverse cross-sectional view on the line 4—4, Fig. 1,

Fig. 5 is an end elevational view of the form of my invention depicted in Figs. 1, 2 and 4, showing the device in position so that the blade may be sharpened, and

Fig. 6 is a longitudinal cross-sectional view of a modified form of my invention.

Describing my invention more in detail, my improvement comprises a base 1 of any preferred configuration and material, such as wood, cast iron, pressed material or the like, and in the form shown in Figs. 1—5 equipped with a cut-out or bored portion 2,

which portion is adapted to house a movable member or jaw 3 provided with a cut-away or bent portion 4 to be engaged by the blade 5 to prevent said blade from slipping. The jaw 3 may be formed of any material in practice found desirable.

Mounted upon the base 1 by any means preferred, such, for example, as by ordinary screws or bolts 6, is a plate 7 of any desired configuration, and material, said plate being equipped with a stationary jaw or member 8, bent over from the plate 7, or associated therewith in any manner desired. If preferred, also, the jaw 8 may be constructed like the jaw 3. The jaws 3 and 4 coact to hold the blade 5 firmly in position so that said blade may be sharpened.

To provide for adjustability, and to accommodate blades of different sizes, a rod 75 or other reciprocating member 9 is positioned in a bored portion 10, said rod being screw-threaded as at 11 to accommodate a ring-nut 12 or other device for adjusting and securing purposes. The rod 9 is provided with a head 13 to engage with the movable jaw 3, and positioned between one wall of the cavity or cut-out portion 2 and the jaw 3 is a helical spring 14, which spring holds the jaw 3 in resilient relation with the blade 5, and thus functions to accommodate blades of different sizes.

As seen more particularly in Figs. 2, 4 and 5, the base 1 may be equipped with an adjustable or pivoted support 15, provided with an element 16, to engage with the base 1 to prevent the device from slipping. The support 15 may be omitted, if desired, as shown in Fig. 3.

In the form of invention depicted in Fig. 3, the elements 1', 2', 3', 4', 5', 7', 8', 9', 10', 11', 12', 13', 14' are precisely formed as previously described in connection with the other form of my invention, and accordingly the description thereof need not be repeated.

In the form of invention depicted in Fig. 6, the base 1'' is equipped with a housing H'', preferably constructed of a suitable material, and in said housing the movable jaw 3'' as well as the rod 9'' are positioned, a set of securing members 6'' of any preferred kind being used to hold said rod in position, the housing H'' being secured to the base 1'' in any manner desired.

The rod 9'' is equipped with a head 13'' to abut against the jaw 3'', which jaw is also

provided with a cut-away portion 4" functioning as previously explained. A helical spring 14" is positioned between the device 6" and the jaw 3', also for a purpose previously described. The threads 11" are provided to me engaged by the wing-nut 12". The jaw 3" moves in an opening 2" corresponding with the cavity 2 of the other form of my invention. The blade 5" is positioned between the stationary jaw 8" as in the other form of my invention.

In operation, the wing nut on either form is loosened, permitting the movable jaw by reason of the action of the spring to move away from the stationary jaw, and the scraper blade is then inserted between the jaws and the wing nut screwed home. If the support 15 is used, it is opened up, and by applying the pressure of the operator's 20 knee to the base, the blade may easily be sharpened by applying a flat file or other sharpening means to the cutting end of said blade by reciprocating said file or said sharpening means over the cutting end of said blade. In the form of my invention depicted in Fig. 5, the base 1' is merely placed upon the floor, or in any other convenient place, and the blade sharpened.

While I have thus described my invention with great particularity, it will be clear that it may be modified throughout a wide range. I accordingly do not propose to be limited to the exact details of construction shown and described, but reserve the right in practice to make any and all modifications thereof that fall within the scope of the appended claims.

I claim as my invention:

1. In a clamp for scraper blades, in combination, a base, a plate of substantial length and width positioned on said base, one end of said plate being upturned to form a stationary jaw, a movable jaw extending up-

wardly through said opening and positioned within said base and adapted for movement relative to said fixed jaw, and a resiliently mounted adjustable means associated with said base and said movable jaw whereby a scraper blade may be adjustably held between said jaw.

2. A clamp for holding scraper blades so that they may be sharpened comprising a base, an integral blade holding member of substantial length and width positioned on said base, a stationary jaw on one end of said member, the other end of said member being provided with an opening, a movable jaw adapted to be reciprocated in said opening and coact with said stationary jaw to hold a scraper blade in fixed position, an adjustable means for said movable jaw free from said stationary jaw, and abutment on said base, and a resilient member associated with said adjustable means and positioned between said abutment and said movable jaw for holding said movable jaw under tension.

3. A clamp for scraper blades comprising a base, a blade holding member on said base, a stationary jaw on one end of said member and positioned between the ends of said base, said member being provided with an opening near its other end, a movable jaw adapted for relative movement with said stationary jaw in said opening, an adjusting device associated with said base and said movable jaw for limiting the movement of said movable jaw, plural means associated with said base for supporting said adjusting device, and a spring on said device for holding said movable jaw under tension, one of said plural means functioning as an abutment for said spring.

In testimony whereof I have signed my name to this specification.

CARL G. E. JOHNSON.
